UNITED STATES PATENT OFFICE.

JAMES HENRY MUSGRAVE, OF BALTIMORE, MARYLAND, ASSIGNOR OF ONE-HALF TO JOHN SIEMON, OF SAME PLACE.

SAFETY ILLUMINATING-GAS DEVICE.

SPECIFICATION forming part of Letters Patent No. 363,343, dated May 17, 1887.

Application filed August 25, 1886. Serial No. 211,860. (No model.)

To all whom it may concern:

Be it known that I, JAMES HENRY MUSGRAVE, a citizen of the United States, residing at Baltimore, in the State of Maryland, have invented certain new and useful Improvements in Safety Illuminating-Gas Devices; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to improvements in safety illuminating-gas devices, wherein is provided a globe which surrounds the gas-flame, and which is so protected by guards that the gas cannot be blown out, either by design or accident, while provision is made for the admission of the proper supply of air to support the gas-flame and for the purpose of lighting the gas. I attain these objects by the device illustrated in the accompanying drawings.

Figure 1 is a side elevation of the gas-bracket with the globe and safety device in section. Fig. 2 is a plan of Fig. 1.

Similar letters refer to similar parts throughout the several views.

The letter A designates the gas-bracket, or a branch of the chandelier, and is constructed of gas-pipe, with the plug-cock B and the burner C, in the manner usually employed.

At the nipple of the pipe a, and held in position by the threaded-burner C, is placed the curved guard-piece d, which serves to prevent the gas from being blown out from beneath, and is provided with the prongs d', to support the globe D at a distance sufficiently great from the said guard d to admit the necessary air for combustion, and at the same time, from the curved form of the said guard d, prevent any draft of air from acting directly upon the flame.

To afford facility for lighting the gas, the trap-door d² in the guard d is provided, which 45 is kept closed by the spring d³.

The globe D is constructed of any translucent material, and is held in position by the spring-prongs d'. Ventilation is afforded at the top of the said globe by the opening d⁴, 50 which is protected by any of the ordinary ventilation-caps, whereby the flame is protected from direct draft.

The manner of operating the device is as follows: The gas is turned on by turning the 55 cock B. The trap-door d² in the guard d is then opened, which will give access to the burner C for lighting; the spring d³ holding the said trap-door closed when the operation is completed. Sufficient space is provided between the guard d and the globe D and in the 60 opening at the top of the said globe to permit proper ventilation.

Having fully described my invention and the manner of operating, what I claim and desire to secure by Letters Patent, is—

In a safety illuminating-gas device, the combination of the supply-pipe a, the burner C, the globe D, cap d⁴, and the guard-plate d, provided with the prongs d', and an opening 70 for lighting the gas, which is protected by the trap door d², the said guard-plate d being secured by means of the burner C and the supply-pipe a, the trap-door d² giving access to the burner for lighting, and the prongs d' serving 75 to hold the globe D in a position whereby sufficient ventilation will be afforded without permitting a direct draft to act upon the flame, for the purpose set forth.

In testimony whereof I affix my signature in 80 presence of two witnesses.

JAMES HENRY MUSGRAVE.
